UNITED STATES PATENT OFFICE.

CHARLES SEYBOLD AND WILLIAM L. VALIQUETTE, OF DAYTON, OHIO, ASSIGNEES TO THE SEYBOLD MACHINE COMPANY, OF DAYTON, OHIO, A CORPORATION OF OHIO.

PAPER-TRIMMING MACHINE.

Application filed March 16, 1922. Serial No. 544,088.

To all whom it may concern:

Be it known that we, CHARLES SEYBOLD and WILLIAM L. VALIQUETTE, citizens of the United States, and residents of Dayton, in the county of Montgomery and State of Ohio, have invented certain new and useful Improvements in Paper-Trimming Machines, of which the following is a full, clear, and exact description, reference being had to the accompanying drawings, forming part of this specification.

Our invention relates to machines for trimming the edges of bundles of paper, pamphlets, books, and the like, in which the bundles of paper are with each single operation of the machine trimmed by the cutting knives for both front and side edges and delivered from the machine, so that the operation is continuous.

20 In machines of this type, as heretofore developed, the most effective construction has provided an intermittently rotating table with a flat upper surface with four stations. At the first station the piles of books 25 to be trimmed are adjusted in position and held by a clamp, the table is then rotated horizontally and a trimming knife at the second station trims one edge, the table again rotates to the third station, where the other edges of the pile are trimmed and the trimmed piles are then carried to the fourth station, where they are delivered.

Other constructions of continuous book trimmers have been also provided, but all 35 embodying a horizontal movement of the piles from one station to another, and in every event to compress and properly hold the bundles under the trimming knives, it has been found necessary to provide a paper clamp acting in conjunction with the cutting knives, the clamp for the cutting knife necessarily being released as the piles were moved from station to station. The accuracy of the cut depends very largely on the pressure of the knife clamp, and this pressure varies with the character of the paper and necessarily exceeds the table clamp pressure. While the table clamps to hold the piles have retained their pressure

as the piles were moved, nevertheless the 50 release of the knife clamp for each successive operation has always tended to permit the piles to shift slightly before the next operation.

With the best of the prior machines the 55 piles of books have always had to be adjusted flat at the receiving station, a matter of considerable difficulty in a continuously operating machine, inasmuch as the natural way to bring a pile of pamphlets into alignment is to jog them on their back edges, holding the pile vertically. The trimmings and waste from the cutting knife have heretofore also accumulated at the several stations requiring a plurality of devices to 60 remove chips, and the three trimming knives located in parallel planes and operating upon the same horizontal table upon which the continued piles are loaded and from which the trimmed piles are removed has 65 rendered the machine one of considerable danger to the operator.

It is to obviate all of these difficulties and to provide a massive and exceedingly powerful continuous book trimmer that our invention is directed, and among the most noteworthy novel features is the construction in which the cutting table is rotated on a horizontal axis with the four stations in planes at right angles to each other and the 70 clamping devices for applying the clamping pressure for the cutting operations are entirely divorced from the knife movements. The piles are held under the requisite powerful variable clamping pressure for extreme accuracy of cut at all times, both when 75 moving from station to station and during the trimming. The piles of books at the loading station are adjusted vertically so that the backs of the packages can be readily jogged into alignment, the chips and cuttings are automatically carried to one station for removal and the completely 80 trimmed bundles are delivered at the lowermost station, whence they can be most easily 85 removed on a traveling carrier.

The invention consists, therefore, of that most novel construction and arrangement of

parts to be hereinafter particularly pointed out and claimed, whereby the above results and numerous others are attained.

In the drawings,

5 Figure 1 is a front elevation of our novel machine.

Figure 2 is an elevation of the left side and

10 Figure 3, an elevation of the right side.

Figure 4 is a rear elevation.

Figure 5 is a perspective view of the cutting table with one of the side plates and part of the clamp mechanism removed.

15 Figure 6 is a perspective view of one of the clamp devices.

Figure 7 is a front elevation of the cutting table showing in dotted lines the internal clamp mechanism.

20 Figure 8 is a detail elevation illustrating the trammel and cam construction for rotating and locking intermittently the cutting table.

Figure 9 is a detail of the ram construction for delivering the trimmed bundles 25 from the machine.

Figure 10 is a cross section on line 10—10 of Figure 9.

Figure 11 is a detail plan view of the clutch and brake band devices.

30 Figure 12 is a front elevation of the knife carrier and knives for making the end cuts.

Figure 13 is a central vertical section of same on line 10—10 of Figure 12.

35 Figure 14 is a detail showing the gearing trains for actuating the knives and rotating the table.

Figure 15 is a plan view of the mechanism for delivering the trimmed books and for removing the paper cuttings and chips.

40 Figure 16 is a perspective view of the pusher bar construction for delivering the trimmed books.

Figure 17 is a detail showing the device to prevent the trimming knives from descending in the event of breakage of the mechanism.

45 Figure 18 is a detail of the knife adjusting devices.

The machine is provided with a framework construction 1 of the solid and massive character required for supporting the various operating parts.

55 In this framework is mounted on a horizontal shaft 2, journaled at front and rear, a substantial cutting table 3, with top, bottom, sides and ends comprising a square box enclosed throughout and the four sides of this box forming a four-sided cutting table adapted to be rotated on a horizontal axis, thus departing entirely from the usual constructions in which the cutting table is rotated on a vertical axis.

60 Each side of the box 3 provides a table for a pile of books to be trimmed. At the first station 4, the packages are jogged up and

properly adjusted and clamped. The table is then rotated a quarter of a revolution, which brings this first pile tightly clamped into position for trimming the front edge at the second station 5, at the same time that a second pile is being adjusted and clamped at the first station 4. The next quarter revolution of the table brings the first pile to the third station 6, where the side edges are trimmed by knives operating simultaneously on the ends of the pile, at the same time the second pile has its front edge trimmed and a third pile is adjusted at the first station. The next quarter rotation advances the first pile now fully 80 trimmed to the last station 7, where the clamp is released and the books delivered from the machine.

The operation of the table is thus intermittent, being held rigid and immovable between each quarter turn, while the cutting knives are operating, but there is no stoppage of the machine for loading or delivering, so that the work of the machine is continuous and adapted for high speed.

90 The four-sided square table 3 is mounted on the horizontal shaft 2 and the table is rotated to carry the bundles to be trimmed from one station to the next by a trammel wheel construction comprising slotted runways 9, 10, 11 and 12, formed of angle pieces securely bolted to the inner side or end of the box table, so as to form four runways at right angles to each other and extending from the four corners of the box to the central shaft, and a stud 13 on the gear wheel 14, as the gear is rotated, is adapted to enter the proper runway and thus rotate the box a quarter revolution, with each rotation of the gear. This gear 14 is mounted on shaft 105 16 and carries a cam 15 (Figure 8), which with each rotation is engaged by the roller 17 on the upper end of the lever arm 18 mounted on the rock shaft 19 on the frame. This rock shaft carries an arm 20 with a 110 flat bearing end which is adapted to swing under and support the box table at one edge, while an arm 21, with a roller 22 at its outer end mounted on a rock shaft 23, supports the table at the other lower edge. These two 115 rock shafts 19 and 23 have depending arms 24 and 25 which are coupled by a rod 26 secured to the lower end of arm 25 and passing through a slotted opening in the other arm 24, while a coiled spring 27 on the rod 26 and bearing between these two arms tends to maintain them in parallel position. The cam surface 15 is so timed in its contact with roller 17 that simultaneously with the entrance of the stud 13 in the trammel, the shaft 19 will be rocked to withdraw the supporting arm 20 and to compress the spring 27. The table is thus released for turning, and just as it reaches a quarter turn the cam 15 releases the arm 18 and the spring 27 130

returns the support to its normal position, the tension of the spring being enhanced by the rock arm 25, which is rocked inwardly by the contact of the edge of the table with the roller 22, the spring 27 also returning the roller 22 to support the table at the other edge.

For feeding the books to be trimmed and clamping them upon the cutting table we provide as follows: On the left side of the machine in line with station 4 we provide a feed trough 30 provided with a bottom 31 and side walls 32, 33, adjustable for various sizes of pamphlets or other material to be trimmed, and in this trough the piles are placed with the backs of the books down, so that they can be easily jogged into alignment.

This feed trough extends up to the loading station 4 on the table and its inner end lies in the pathway of the table as it is rotated. We therefore provide for swinging the trough out of the way as the table is rotated. The feed trough is supported on a vertical standard or frame 150 which extends down along the side of the main framework and is formed with a bearing which is keyed to the horizontal shaft 142, suitably mounted on the frame. This shaft has keyed to it at the inner end a sleeve 143 which carries an arm 145 which extends upwardly to the top of the table and thus serves as a vertical support for the table. The standard 150 and arm 145 are held under spring tension by the spring 146 (Figure 1) bearing between a bracket 147 on main frame and a lug on the lower end of the standard. When the table is rotated, the movement tips or swings the feed trough outwardly into the position indicated by dotted lines in Figure 1, thus allowing the lower edge of the table to pass, and the spring 146 brings the parts back to normal.

On the table at each of the four stations (Figure 7) there is secured a back gauge 34 and a cutting board 35 and a side gauge 36 all adjustable as is usual for such machines. The pattern board 37, of desired size, is secured to the holder 38, which is swiveled at the outer end of the clamp arm 39, which is securely bolted to the clamp bar 40.

These clamp bars 40, one for each clamp device, extend into the inside of the enclosed cutting table through suitable openings, and each clamp is actuated by a powerful lever 41, one for each clamp. These levers are pivotally mounted on short shafts mounted in bearings 42^a, in transverse plates 149 spaced apart near the middle of the table box and each lever carries on its inner end a roller 43, which bears against a cam 44 on the shaft 2. As the shaft 2 is stationary and the cutting table rotates these rollers are pressed outwardly by the cam 44. The inner portion of each clamp bar 40 is formed into

a hollow box 151 closed at the inner end except for a small sized opening. Seated in this box is a heavy coiled spring 47 and inside the coils of spring 47 is a lighter spring 48 which projects through the opening in the end of the box and bears against the end wall. A pin 45 is mounted transverse the sides of the box. Each lever 41 is formed with a nose 152 which engages between the pin 45 and a washer 46 interposed between the lever and the coiled springs.

When the high portion of the cam 44 engages a roller on the lever 41, the clamp will be brought down to the paper pile and caused to engage and hold its respective pile under the tension of the spring 47. As soon as the lever is released from the cam, the lighter spring returns the parts to normal and releases the clamp.

In order to adjust the position of the cam, the shaft 2 extends through the bearings of the cutting table and is provided with a disk 50 having a notch 51 engaged by a spring-pressed pin or latch 52 mounted in the casting 53. As long as the disk is held locked by this latch 52 the clamp pressure will be maintained by the cam 44, but should the pressure become too great, the disk, and with it the cam, will be released to turn with the cutting table.

It will be noted also that the cam 44 is so disposed with relation to the operating levers, that when the side of the table reaches the bottom station, the clamp will be released and that the clamp at first station will also be released and that as the table is started from this station, the clamp is at once applied to rigidly hold the pile from that point past the two trimming stations to the delivery station.

At the second station 5, the front edge of the pile is trimmed and at the third station 6, the two ends are trimmed. Of course, it will be understood that this order of trimming is merely a matter of preference and that the two parallel knives could be arranged to trim first.

For operating the knife we provide a massive frame of side walls and arch 55 in which is journaled the shaft 56 in bearing 57. This shaft is coupled by a segment gear 58 with a rack 58^a on the knife carrier 59, which is mounted to slide in a dovetailed runway 60 in the frame. The knife frame 61, to which the knife 62 is bolted, is mounted by a dovetail mortise 63, so that it can be adjusted laterally for the front edge of the package to be trimmed.

The shaft 56 is rocked in timed relation to the arrival of the clamped package for actuating the knife by the crank arm 64 coupled by yoke 65 to the rod 66, which is in turn coupled to the crank arm 67 on shaft 68 journaled in the frame. This shaft 68 carries a gear 69, which is engaged by

pinion 70 on the end of shaft 71 with journal bearings 72, 73, on the side of the frame. The other end of shaft 71 carries a gear 74 which meshes with pinion 75 on the inner end of the driving shaft 76. Loosely mounted on the outer end of the driving shaft is a driving pulley 77 and fly wheel 78 with hub band 79 within which is mounted an expansion band clutch member 79^a, which is expanded by the sliding collar 80 keyed to but sliding on the driving shaft. This collar is shifted to couple the driving pulley to the driving shaft by the arm 81 mounted on the shaft 82, which is actuated by the rock arm 83 on the shaft 84. This shaft 84 extends across the machine and is provided with the hand lever 85 by means of which the machine is started. To stop the mechanism when the expansion clutch is released, we provide a brake band 86 to engage a hub band 86^a on the driving shaft. This brake band is held under spring tension in the usual way and adjusted by the tension rod 87 operated by hand wheel 88. The open ends of the brake band have bosses with rollers 89 which are adapted to be engaged by a wedge shoe 90 carried by a rod 91, which is attached to a collar 92 on shaft 82. When the shaft 82 is shifted by the starting lever to throw in the clutch, the wedge shoe 90 will be forced in between the bosses 89 on the brake band and thus will release the brake, and when the clutch is thrown out, the wedge will be withdrawn, permitting the brake band to engage the hub band on the driving shaft.

The gear 69 on shaft 68 carrying the crank arm 67 which actuates the front knife also meshes with the gear 14 on shaft 16 which carries the stud engaging the trammel on the cutting table and the action is timed to permit the quarter rotation and locking of the table before the knife reaches the paper piles.

The end cuts of the paper pile are made simultaneously with the front cut of the next package to be trimmed and to accomplish this, the shaft 68 is also provided with a crank arm 121 coupled by connecting rod 120 and yoke 122 to the knife frame 95 upon which the two knife carriers 94, 94, are mounted. The knife frame 95 is beveled to slide in a dovetailed groove in the head 96 of the frame as the crank arm 121 on the knife driving shaft 68 is operated. The knife carriers 94, 94, are mounted on the knife frame by tongue and mortise and are adjustable towards and away from each other by the adjusting screw to determine the width of the end cuts. As it is important that the knives shall cut entirely through the pile, the knives are made in two parts, as shown in Figure 18. The knife shank 98^a is bolted to the knife carrier and the knife blades 98^b are separated and

adapted to be adjusted lengthwise in the knife shank by the adjusting screws 99.

When the trimmed package reaches the final station at the bottom of the table and the clamp is released as heretofore described, the package is automatically delivered to an endless traveling belt 101 for delivery from the machine by a pusher 102 on the end of a push bar 103 (guided in casing 160 secured in the frame) and coupled to a rock arm 104 on a rock shaft 105 journaled in bearings at the bottom of the frame at the rear. This rock shaft has an arm 106 carrying a vertical rod 107, which loosely engages an eye 108 on a collar 109 secured to the rock shaft 56, which drives the front knife and a coiled spring 110 bears between the eye 108 and the arm 106. Thus with each operation of the knife at the first trimming station, the pusher bar is actuated to deliver the fully trimmed piles at the delivery station.

In order that the pusher plate 102 may be readily adjusted for piles of varying sizes, we prefer to construct the pusher plate of L-shape, as shown in Figure 16. Both arms of the L are provided with slots 161 and 162 on the base of grooves 163, 164, and the pusher bar 103 is provided with a tongue 165 to fit in either groove and held in adjusted position by the screw bolt 166. In this way while the pusher bar 103 is held in upright position the pusher plate can be shifted into any position desired to cover any size of package.

At the same time that the trimmed packages are delivered, arrangement is made for removing the cuttings and chips which have been severed by the trimming knives. The four-sided cutting table lends itself most effectively both for the delivery of the trimmed books and also for the removal of cuttings. At the same time that the trimmed books reach the bottom station, the chips, which have accumulated when the cutting surface was in horizontal position and which are the result of the end cuts, drop down and are deposited upon an endless traveling belt 128 running over drums 128^a and 128^b.

The traveling belts for both the chips and the book delivery are operated by the same mechanism.

Mounted on the front end of the shaft 71 is a pulley 123 carrying a belt 124 which is turned at right angles by the idlers 124^a to drive a pulley on the shaft which carries the front drum 128^b. To insure the proper drive of the belt 128, we prefer to mount on the pulley shaft a pair of sprocket wheels with sprocket chains 127 running over idler sprockets on the drum 128^a. On the far end of the pulley shaft an additional sprocket is mounted which carries a sprocket chain 130 which runs over idler sprockets 140 and thence in opposite directions over 130

the sprockets 131 and 132. The front sprocket 131 also drives the front roller 133 over which and the inner roller 133^a the endless belt 101 runs by which the trimmed books are delivered, and both the belt for chips and the book delivery belt are made up of strips spaced slightly apart as shown.

As the books are delivered automatically by the pusher 103, it is necessary to have the 10 receiving belt 101 in a position to receive any sizes of books and therefore it will be necessary to adjust the endless belt construction longitudinally. For this reason the framework 134 in which the parts are 15 carried is mounted for such movement and arranged to be adjusted by the screw 135.

In order that the heavy weight of the knife carriers and other parts in the event of some accident or breakage should not 20 cause the machine to run backward and the knives descend, we provide a device to prevent such occurrence (Figure 17). Mounted on the shaft 76 is keyed a collar 170 in contact with a plate 171 bolted to the frame- 25 work. This plate has pivoted on it a plurality of spring-pressed dogs 172 with cam ends which engage the periphery of the collar 170. The cam surfaces of these dogs are so formed that with the shaft rotating 30 in its normal driving direction, the dogs lie loosely on the collar. Should, however, the shaft 76 be turned in the opposite direction, the dogs will immediately lock the shaft.

We have illustrated the driving power of 35 the machine as furnished by an electric motor 112 mounted on the side of the frame with the pulley 113 on the armature shaft connected with the driving pulley 77 by belt 114, but, of course, the power may be 40 furnished in any other way.

The operation of the machine has been fully described in connection with the detailed description of the parts so that it would hardly seem necessary to repeat.

45 It will, of course, be understood that there are many well known mechanical equivalents for driving the various parts in timed relation, and that the failure to mention such equivalents is not to be considered as 50 evidencing any intention on our part to limit our invention to the specific devices shown. In illustrating specific mechanism it is to be understood that such mechanism embodies our preferred construction only 55 and it is not to be understood as limiting us to such specific structures.

Having thus described our invention, what we claim as new and desire to secure by Letters Patent, is:—

60 1. In a paper trimming machine, the combination with a plurality of trimming devices arranged in different planes to operate on different portions of a paper pile in succession, of means for presenting the piles to said trimming devices, said means being

in planes at an angle to each other with yieldable clamps to hold the piles while being trimmed.

2. In a paper trimming machine, the combination with a plurality of trimming devices arranged in different planes to operate on different portions of a paper pile in succession, of a cutting table with yieldable clamping devices to hold the paper piles, and means for shifting the table to present 70 the piles in succession to the several trimming devices.

3. In a paper trimming machine, the combination with a plurality of trimming devices arranged in different planes to operate 80 on different portions of a paper pile in succession, of a cutting table comprising a plurality of sections disposed in planes at an angle to each other, and means for shifting the table to bring the several sections into 85 position under the trimming devices with yieldable clamps to hold the piles while being trimmed.

4. In a paper trimming machine, the combination with a plurality of trimming devices arranged in different planes to operate 90 on different portions of a paper pile in succession, of a cutting table comprising a plurality of sections disposed in planes at right angles to each other, and means for rotating 95 the table intermittently, to bring the several sections into position under the trimming devices with yieldable clamps to hold the piles while being trimmed.

5. In a paper trimming machine, the combination with a plurality of trimming devices arranged in different planes to operate 100 on different portions of a paper pile in succession, of a cutting table comprising a plurality of sections disposed in planes at right angles to each other, and means for rotating 105 the table intermittently, on a horizontal axis, to bring the several sections into position under the trimming devices with yieldable clamps to hold the piles while being trimmed.

6. In a paper trimming machine, the combination with a plurality of trimming devices arranged in different planes to operate 110 on different portions of a paper pile in succession, of a cutting table with yieldable clamping devices to hold the paper piles, and means for shifting the table to present the piles in succession to the several trimming devices, said cutting table comprising 115 a plurality of sections disposed in planes at an angle to each other.

7. In a paper trimming machine, the combination with a plurality of trimming devices arranged in different planes to operate 120 on different portions of a paper pile in succession, of a cutting table with yieldable clamping devices to hold the paper piles, and means for shifting the table to present the piles in succession to the several trimming 125 devices.

devices, said cutting table comprising a plurality of sections disposed in planes at right angles to each other.

8. In a book trimming machine, the combination with a plurality of reciprocating trimming knives arranged to operate simultaneously on different parts of a succession of piles of paper, of means for reciprocating the trimming knives for successive cuts in different planes, and a cutting table for holding the piles, and means for rotating the table to present different portions of the table to the action of the trimming knives in succession with yieldable clamps to hold the piles while being trimmed.

9. In a book trimming machine, the combination with a plurality of reciprocating trimming knives arranged to operate simultaneously on different parts of a succession of piles of paper, of means for reciprocating the trimming knives for successive cuts in planes at right angles to each other, and a cutting table comprising sections at right angles to each other upon which the piles of paper are clamped, and means for rotating the table to present the table sections carrying the clamped piles simultaneously to the action of the trimming knives.

10. In a paper trimming machine, a rotatable cutting table comprising a plurality of table sections in planes at right angles to each other, a clamp for each table section with a pulling bar for each clamp mounted on and rotatable with the table, and means on the table for holding the clamps under tension as the table is rotated.

11. In a paper trimming machine, a rotatable cutting table comprising a plurality of table sections in planes at right angles to each other, a clamp for each table section with a pulling bar for each clamp mounted on and rotatable with the table, an actuating lever for each bar, and means for bringing said levers into operation, with springs interposed between each lever and its respective bar to maintain the clamp under spring tension.

12. In a paper trimming machine, a rotatable cutting table comprising a plurality of table sections in planes at right angles to each other, a clamp for each table section with a pulling bar for each clamp mounted on and rotatable with the table, an actuating lever for each bar, and a fixed cam for actuating said levers, with springs interposed between each lever and its respective bar to maintain the clamp under spring tension.

13. In a paper trimming machine, a cutting table rectangular in cross section, comprising four cutting surfaces at right angles to each other, and means for rotating same on a horizontal axis, trimming knives and means for reciprocating them to trim paper piles at successive stations at right angles to each other simultaneously with yieldable

clamps to hold the piles while being trimmed.

14. In a paper trimming machine, a cutting table rectangular in cross section, comprising four cutting surfaces at right angles to each other, a trimming knife for trimming the front side of a paper pile and a pair of trimming knives for trimming the ends of the pile, means for actuating said knives simultaneously in planes at right angles to each other to trim successive paper piles on adjoining cutting surfaces, and means for intermittently rotating the cutting table to bring the paper piles in succession to said knives with yieldable clamps to hold the piles while being trimmed.

15. In a paper trimming machine, a cutting table rectangular in cross section, comprising four cutting surfaces at right angles to each other, a trimming knife for trimming the front side of a paper pile and a pair of trimming knives for trimming the ends of the pile, means for actuating said knives simultaneously in planes at right angles to each other to trim successive paper piles on adjoining cutting surfaces, and means for intermittently rotating the cutting table on a horizontal axis to bring the paper piles in succession to said knives with yieldable clamps to hold the piles while being trimmed.

16. In a paper trimming machine, a cutting table rectangular in cross section, comprising four cutting surfaces at right angles to each other, a trimming knife for trimming the front side of a paper pile and a pair of trimming knives for trimming the ends of the pile, means for actuating said knives simultaneously in planes at right angles to each other to trim successive paper piles on adjoining cutting surfaces, and means for intermittently rotating the cutting table to bring the paper piles in succession to said knives, with yieldable clamps upon each table section to hold the paper piles under cutting pressure during the table rotation and the trimming operations.

17. In a paper trimming machine, a cutting table rectangular in cross section and comprising four operating stations at right angles to each other, a loading station, two trimming stations and a delivery station, each station being provided with a yieldable clamp to hold the paper to be trimmed, trimming knives operable at the trimming stations, means for intermittently rotating the table on a horizontal axis to carry the piles from station to station, with means to actuate the clamp at the loading station and to release the clamp at the delivery station.

18. In a paper trimming machine, a cutting table rectangular in cross section and comprising four operating stations at right angles to each other, a loading station, two trimming stations and a delivery station,

each station being provided with a yieldable clamp mounted on the table to hold the paper to be trimmed, trimming knives operable at the trimming stations, means for intermittently rotating the table on a horizontal axis to carry the piles from station to station, with means to actuate the clamp secured to a relatively fixed portion of the machine and brought into operation at the loading station and releasable at the delivery station.

19. In a paper trimming machine, a rotatable cutting table comprising a loading station and a trimming station at an angle to each other, a feed trough for feeding the material to be trimmed to the loading station, and means for tipping the feed trough out of the pathway of the table during its rotation.

20. In a paper trimming machine, a rotatable cutting table comprising a plurality of table sections in planes at an angle to each other, a yieldable clamp for each table section with a pulling bar for each clamp mounted on and rotatable with the table, an actuating lever for each bar, and a cam relatively fixed with which said levers contact to close each clamp during a portion of the table rotation and to release the clamp during the remaining portion of the rotation.

21. In a paper trimming machine, a rotatable cutting table comprising a plurality of table sections in planes at an angle to each other, a trimming knife for one section and a pair of trimming knives for another section, a clamp for each table section with a pulling bar for each yieldable clamp mounted on and rotatable with the table, an actuating lever for each bar, and a cam relatively fixed with which said levers contact to close each clamp at and between the trimming stations and to release the clamp at the remaining stations.

22. In a paper trimming machine, comprising a rotatable cutting table having a plurality of table sections at an angle to each other and trimming knives operable in planes at an angle to each other, a driving shaft and train of gearing for reciprocating said trimming knives and a trammel wheel device with connection with said gearing for rotating the cutting table in timed relation with the movement of the trimming devices, whereby the trimming operations may be accomplished when the table is at rest.

23. In a paper trimming machine comprising a rotatable cutting table having a plurality of table sections at an angle to each other and trimming knives operable in planes at an angle to each other, a driving shaft and train of gearing for reciprocating said trimming knives and a trammel wheel device with connection with said gearing for rotating the cutting table in timed relation

with the movement of the trimming devices, with means for locking the table in fixed position during the trimming operations.

24. In a paper trimming machine comprising a rotatable cutting table having a plurality of table sections at an angle to each other and trimming knives operable in planes at an angle to each other, a driving shaft and train of gearing for reciprocating said trimming knives and a trammel wheel device with connection with said gearing for rotating the cutting table in timed relation with the movement of the trimming devices, with means for locking the table in fixed position during the trimming operations, and means for releasing the table from said lock at the commencement of the trammel wheel actuation.

25. In a paper trimming machine, in combination with a cutting table comprising a plurality of operating stations at an angle to each other, and means for intermittently rotating said table on a horizontal axis, of a reciprocating rod carrying a push plate, and means for reciprocating the rod in timed relation to the table rotation to contact with the paper pile at the final station to deliver the same from the table.

26. In a paper trimming machine, in combination with a cutting table comprising a plurality of operating stations at an angle to each other, and means for intermittently rotating said table on a horizontal axis, of a reciprocating rod carrying a push plate, and means for reciprocating the rod in timed relation to the table rotation to contact with the paper pile at the final station to deliver the same from the table, with an endless belt and means for driving same by the machine mechanism to automatically deliver the paper piles from the machine.

27. In a paper trimming machine, in combination with a cutting table comprising a plurality of operating stations at an angle to each other, and means for intermittently rotating said table on a horizontal axis, of a reciprocating rod carrying push plate, said push plate comprising an L-shaped slotted plate whereby the plate may be adjusted into various positions, and means for reciprocating the rod in timed relation to the table rotation to contact with the paper pile at the final station to deliver the same from the table.

28. In a paper trimming machine, the combination with a plurality of trimming devices arranged to trim different parts of books in succession, of a book presenting means, means for operating the trimming devices to effect the trimming operations in different planes, and yieldable clamping mechanism for holding the books under clamping pressure independent of the operation of the trimming devices.

29. In a paper trimming machine, the com-

bination with a plurality of reciprocating cutters arranged to trim different parts of books in succession, of a book presenting means, means for reciprocating the cutters in planes at an angle to each other to effect successive trimming operations in different planes, means for presenting the successive books to said cutters, with yieldable clamping mechanism for holding the books under variable pressure independently of the trimming devices.

30. In a paper trimming machine, the combination with a plurality of reciprocating cutters arranged to operate on different parts of books in succession, of means for simultaneously reciprocating said cutters to effect successive trimming operations in different planes, a book presenting means comprising a rotary member with a plurality of book holding stations thereon in different planes, means for rotating said member on an axis at right angles to the planes of movement of the reciprocating cutters to 40 present the books in succession to said cutters, whereby the chips from the books will be shifted from station to station, and an endless belt conveyor located under the final station to receive the chips, with means for driving said conveyor operated by the machine mechanism to remove the chips automatically from the machine.

tatable with the rotary member to hold the books under variable pressure for trimming independent of the cutters.

31. In a paper trimming machine, the combination with a plurality of reciprocating cutters arranged to operate on different parts of books in succession, of means for simultaneously reciprocating said cutters to effect successive trimming operations in different planes, a book presenting means comprising a rotary member with a plurality of book holding stations thereon in different planes, means for rotating said member on an axis at right angles to the planes of movement of the reciprocating cutters to 40 present the books in succession to said cutters, whereby the chips from the books will be shifted from station to station, and an endless belt conveyor located under the final station to receive the chips, with means for driving said conveyor operated by the machine mechanism to remove the chips automatically from the machine.
